BOOKMARK

Edwin A. Ross, New York, N.Y., assignor to Lawrence Ross, Baldwin, N.Y.

Filed Nov. 22, 1963, Ser. No. 77,546

Term of patent 14 years

(Cl. D6—2)

I claim:

The ornamental design for a bookmark, substantially as shown.
